UNITED STATES PATENT OFFICE.

HENRY W. WINTER, OF METHUEN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

STAMPING-MACHINE.

1,381,153.

Specification of Letters Patent. Patented June 14, 1921.

Application filed March 23, 1917. Serial No. 157,037.

To all whom it may concern:

Be it known that I, HENRY W. WINTER, a citizen of the United States, residing at Methuen, in the county of Essex and State 5 of Massachusetts, have invented certain Improvements in Stamping-Machines, of which the following description, in connection with the accompanying drawings, is a specification, like reference characters on 10 the drawings indicating like parts in the several figures.

This invention relates to machines for marking, stamping or embossing sheet material, such for example, as parts of boots 15 and shoes.

Metallic stamping medium such as gold leaf, is supplied for stamping purposes in the form of a long strip with a paper backing wound into a coil. An object of the 20 present invention is to provide improved mechanism for automatically supplying such stamping medium in strip form so that the stamping machine may be operated without requiring the operator to do more than 25 present the work in stamping position.

Features of the invention consist in improved guiding means whereby the strip may be conducted to and away from a movable die, and improved feeding means 30 which may be so regulated as to supply in accurate measure the amount of stamping medium required by the die in use.

As herein shown a heated die is employed and means are provided for guiding the 35 stamping strip into sufficiently close proximity to the die to insure its proper location at the moment when the die is pressed upon the work, while at the same time maintaining the strip between the stamping operations sufficiently remote from the die to prevent 40 overheating of the strip.

These and other features of the invention will be best understood and appreciated from the following description of a preferred embodiment thereof selected for purposes of illustration and shown in the accompanying drawings, in which—

Figure 1 is a view in perspective of the entire machine;

Fig. 2 is a view in side elevation, partly in section;

Fig. 3 is a sectional view of the supply reel;

Fig. 4 is a sectional view of the strip guid-

ing devices adjacent to the supply reel, and 55 Figs. 5 and 6 are sectional views of the strip feeding mechanism.

The lower portion of the machine frame is provided with a vertical bore to receive the shank of the work plate 4 which is adjustably supported in the frame by a nut 6. The upper branch of the frame is provided with vertical ways for a head 9 in which is yieldingly and adjustably mounted the 60 stem 8 of the die carriage. The position of 65 the die carriage with respect to the head 9 may be adjusted by a nut 26 threaded upon the upper end of the stem 8 while a compression spring interposed between a shoulder on the stem 8 and an adjustable bearing 70 piece 27 affords relief in case of excessive pressure. The head 9 is reciprocated vertically by a lever 28 journaled upon a cross shaft 30 in the machine frame and operated through a vertical link 32 from a cam 35. 75 The cam 35 is fast upon a cam shaft 38 and has a cam groove 36 in which runs a roller 34 on the link 32. The mechanism above described is similar to that disclosed in my prior application Serial No. 870,700, filed 80 November 6, 1914, and forms no part of the present invention.

A removable die block 10 is mounted in ways formed in the die carriage. The die block is bored laterally to receive an electric 85 heating unit 12 and provided on its lower face with an undercut recess to receive the die 14. One side of the recess is formed by a slideable plate 16 which is normally pressed into engagement with the undercut portion 90 of the die by a spring 18 which is mounted on the die block and acts at its lower end against the rear side of the plate 16. The die block is provided with an opening extending from front to rear and through this 95 opening extend a pair of sheet metal shields 20 and 22. The shields 20 and 22 are secured to the rear side of the die block 10 and extend forward through the opening and then downwardly over the front side 100 of the die block. At their lower edges the shields 20 and 22 are brought together and secured to an intermediate sheet of asbestos 24. The shields are of light spring metal and are spaced from the die block so as to 105 be kept cool by the interposed air spaces. The lower edge of the asbestos sheet extends downwardly below the face of the die 14

and when the die is depressed the edge of the asbestos sheet encounters the work in advance of the die and is forced upwardly against the action of the spring shields. 5 When the die is elevated from the work the edge of the asbestos sheet acts as a stripper to separate the stamping strip from the face of the die.

The frame 2 is provided with a pair of ears to receive a cross rod 81 upon which the reel 80 of stamping strip 70 may be loosely mounted. As shown in Fig. 3, a set screw 83 is provided for retaining the cross rod 81 in position. Upon one end of the rod there 10 is provided a detachable head 85 having a curved binding spring 86 which is perforated to receive the end of the rod 81 and so arranged as normally to cramp on the rod and so prevent axial movement of the head 85. The head 85 bears against one end of the reel 80 and a compression spring 84 upon the rod bearing against the opposite end of the reel creates sufficient friction 15 to prevent loose running of the reel.

25 Adjacent to the front side of the reel 80 is provided a pair of transverse guide rods 87, 88 between which the stamping strip is led on its way to the die. The rods 87, 88 are carried by a pair of arms 91 adjustably 20 mounted on a right and left screw 89 which is held in position by frictional engagement with a lug on a portion of the machine frame. The arms 91 act as edge gages for the stamping strip and may be moved toward or from each other in accordance with the width of the strip being used by turning the right and left screw 89 in the appropriate direction. The rods 87 and 88 25 also coöperate with the lower edge of the asbestos sheet 24 in guiding the stamping strip across the lower face of the die.

A feed roller 90 journaled upon cross-shaft 65 is provided at the rear of and above the supply reel 80. The feed roller is secured to the shaft 65 by a set screw shown in Fig. 6 and to the left end of the shaft is keyed the inner member 64 of a one-way clutch. This member 64 is received in the inner face of a head 63 loosely mounted upon the outer end of a shaft 65 and having a projecting arm 60. The arm 60 is slotted to receive an adjustable block 59, the position of which may be radially adjusted by a screw 62 carried by the arm 60. A feed 30 link 56 is connected to the block 59 at its upper end and at its lower end is connected to a lever 46 pivoted upon a cross-shaft 48 (see Fig. 2). The lever 46 is loosely mounted on the shaft 48 and its rear end 52 is provided with a locking stud 54 by which the arm 52 may be detachably locked to an arm 50 fast on the shaft 48 and projecting rearwardly therefrom. The lever 46 carries a cam roller 44 arranged to run in a cam track 35 42 in the inner face of a cam 40 on the shaft 65 38. When the end of the lever 52 is locked to the arm 50 the cam operates to oscillate the arm 60 through the link 56 and so turn the feed roller 90. The extent of its oscillation and consequently the length of the feeding movement imparted to the strip is adjusted by moving the block 59 nearer to or farther from the axis of the arm 60. A co-operating feed roller 96 journaled upon a shaft 95 is provided adjacent to the feed 40 roller 90. The roller 96 is positively driven by a geared connection with the roller 90. The ends of the shaft 95 are received in 45 slideable journals which are normally forced toward the roller 90 by springs as shown in Fig. 6, so that the stamping strip may engage yieldingly with a uniform pressure.

A pair of side gages 93 are disposed adjacent to the upper surface of the feed roller 90, being carried upon a right and left screw 40 92 set in the portion 94 of the machine frame. These gages may be adjusted toward or from each other in accordance with the width of the stamping strip and together with the feed roller 90 serve to direct the stamping strip to the upper shield 20 of the die block.

The machine is made ready for operation by inserting the coil of stamping medium 70 upon the supply reel 80 and leading the end 45 of the stamping strip between the guide rods 87 and 88, then over the shield 20 to the feed rolls 90, 96 from which the end of the strip passes downwardly into the column of the machine standard. The length of the feeding space is then adjusted by turning the screw 62 so that the strip will be advanced after each operation just sufficiently to bring fresh material beneath the face of the die 14.

In operating the machine the work is presented in position upon the plate 4 and the machine started. The stamping head is immediately lowered and the die 14 pressed against the work and upon the strip of stamping material. In this operation, as already explained, the shields 20 and 22 yield slightly and then reassume their normal position causing the asbestos sheet 24 to strip the die. As the stamping head moves upwardly the arm 60 is oscillated advancing the stamping strip in readiness for the ensuing operation.

Having thus described my invention, I claim as new and desire to secure by Letters Patent of the United States:

1. A stamping machine, having, in combination, a movable die having strip guiding means, a supply reel and a feed roller rotatable about fixed axes located at one side 125 of the path of the die, whereby a strip of stamping medium may be looped about the die between the reel and feed roller.

2. A stamping machine, having, in combination, a reciprocatory die, a feed roller located at one side of the path of the die, a supply reel for a strip of stamping medium located upon the same side of the path of the die, and guiding means directing the strip from the reel to the feed roll about the die and out of contact therewith. 40
- 5 3. A stamping machine, having, in combination, a reciprocatory die carrier having a stamping die and a recess formed about the die, and means for guiding a strip of stamping medium through the recess and across the face of the die. 45
- 10 4. A stamping machine, having, in combination, a reciprocatory die carrier having a stamping die and an opening disposed substantially parallel to the face of the die, strip guiding means, and means for feeding a strip of stamping medium through the opening and past the face of the die. 50
- 15 5. A stamping machine, having, in combination, a reciprocatory die carrier having a stamping die, and means movable with the carrier for guiding a strip of stamping medium in a loop about the die and normally out of contact with the die. 55
- 20 6. A stamping machine, having, in combination, a reciprocatory die carrier having a spaced end portion, means for heating said end portion, and means for guiding a strip of stamping medium in a loop about said end portion. 60
- 25 7. A stamping machine, having, in combination, a reciprocatory die carrier having a spaced end portion, means for heating said end portion, and guiding means extending into the space for guiding a strip of stamping medium about said end portion while maintaining the strip out of contact therewith. 65
- 30 8. A stamping machine, having, in combination, a reciprocatory die carrier having a heated end portion and a shield fixed to the carrier for engagement with the stamping medium disposed opposite to two surfaces of said end portion and separated therefrom to furnish an air space between the stamping medium and heated portion of the die. 70
- 35 9. A stamping machine, having, in combination, a heated die carrier, and a shield comprising two sheet metal members spaced from the carrier and from each other. 75
- 40 10. A stamping machine, having, in combination, a heated die carrier, a die, a support fixedly secured to a wall of the carrier, and an asbestos stripper mounted upon the support and constructed and arranged to engage the work through a strip of stamping medium during the stamping operation. 80
- 45 11. A stamping machine, having, in combination, a movable stamping die, a supply reel for stamping medium in strip form, guide rods for the strip of stamping medium, and adjustable edge gages carried by said rods. 85
- 50 12. A stamping machine, having, in combination, a stamping die, a driven take-up roller for drawing a strip of stamping medium over the die, and adjustable edge gages coöperating with the strip opposite and in close proximity to the surface of the roller, the strip passing immediately between the edge gages and the roller. 90
- 55 In testimony whereof I have signed my name to this specification. 95
